UNITED STATES PATENT OFFICE.

LYTER H. CRAWFORD, OF NEW YORK, N. Y.

COMBINED MOUTH MIRROR AND LAMP.

No. 849,209.

Specification of Letters Patent.

Patented April 2, 1907.

Application filed April 25, 1906. Serial No. 313,585.

To all whom it may concern:

Be it known that I, LYTER H. CRAWFORD, a citizen of the United States, residing at New York, in the county of New York and State of New York, have invented certain new and useful Improvements in a Combined Mouth Mirror and Lamp; and I do declare the following to be a full, clear, and exact description of the invention, such as will enable others skilled in the art to which it appertains to make and use the same.

This invention relates generally to dental appliances, and particularly to a combined dental mouth mirror and lamp; and it has for its object to provide a simple, durable, and comparatively inexpensive device embodying on one handle a mouth mirror and a lamp, whereby the accumulation of moisture from the breath of the patient on the mirror is prevented and the dentist is enabled to immediately illuminate the mouth for the purpose of making a thorough examination of the teeth and gums on dark or cloudy days and at night preparatory to treating the same; and it consists in the parts and combinations of parts hereinafter described and claimed.

In the accompanying drawings, forming a part of this specification, Figure 1 is a longitudinal section through my invention. Fig. 2 is a side elevation of the same with the sliding collar for making and breaking the lamp-circuit removed. Fig. 3 is a side elevation of the completed device. Fig. 4 is a fragmentary detail view of a part of the handle. Fig. 5 is an enlarged detail vertical section through the lamp-casing.

Similar letters refer to similar parts throughout the several views.

Referring to the drawings, A represents a hard-rubber or gutta-percha handle, preferably tapered in shape and having its ends reduced and screw-threaded. The handle is formed tubular or with a central longitudinal opening a for the passage of the twisted flexible cords or wires B, which lead the current to the lamp, as will be described.

A metal cap C, perforated to correspond to the opening a in the handle, is screwed onto the enlarged or butt end of the handle, and a tubular metal extension or neck D is screwed onto the smaller end of the handle, said neck having its free end cupped or expanded to form a half-spherical socket b, which, with the similarly formed but smaller ball c, formed

at the end of a neck d, projecting from the rim of the mirror and lamp casing E, forms a ball-and-socket joint between said casing and the handle, whereby the former may be turned and tilted or adjusted to any desired angle.

The socket b is split or divided, as at e, to enable the ball c to be readily inserted therein, and both the neck D and the neck d are tubular to correspond to and form a continuation of the opening in the handle.

The casing E is annular in form and receives on one side a mirror F, and on the opposite side a lens G is framed. The mirror and the lens are secured in the rim-casing in any desired or preferred manner.

Within the casing the insulating-blocks f are secured, one at each side of the point where the neck d opens into the casing, and to these blocks are secured the brass plates g by the screws h, to which the conductor-wires B B' are connected. Between the plates g a circular or annular shaped flat lamp or bulb L is supported by the wires i, which are supported by said plates, and between said wires i the filament j is arranged.

One of the current lead-wires B is connected to one of the screws h within the casing and the other to the contact-screw k in the recess H, formed in the handle A, and a conductor-wire B' connects the other screw h to the screw l in said recess.

A brass contact-spring m is secured within the recess H and is bent so as to lie within the path of a screw or pin n, which is carried by a sliding collar I, arranged on the handle A in order to make and break the lamp-circuit. The collar I also carries a screw o, which extends into a groove p, formed in the handle, in order to limit the movement of the collar on the handle and prevents its accidental removal or displacement.

Thus it will be observed that I provide in one instrument or tool means for reflecting the gums and teeth, and that the mirror is kept dry or clear of moisture from the breath of the patient by the heat generated by the lamp, and that the latter enables the dentist to make a thorough inspection of the mouth on dark and cloudy days and at night without recourse to awkward and cumbersome means for focusing the light, and that the casing containing said mirror and lamp may be readily adjusted to any desired angle or position.

Having thus described my invention, what I claim as new, and desire to secure by Letters Patent, is—

1. A combined mouth mirror and lamp for dental use comprising a casing provided with illuminating and reflecting mediums mounted universally adjustable on a handle.
2. A combined mouth mirror and lamp for dental use comprising a handle, a mirror, and an electric lamp said mirror and lamp being adjustably mounted on said handle, and means for making and breaking the lamp-circuit carried by said handle.
3. A combined mouth mirror and lamp comprising a handle, a casing adjustably mounted on said handle, a mirror mounted on said casing, a lens mounted opposite said mirror, and a flat electric lamp arranged between said mirror and lens.
4. A combined mouth mirror and lamp for dental use comprising a handle, a casing ad-

justably connected to said handle, a mirror mounted on said casing, a lens mounted opposite said mirror, a flat electric lamp arranged between said mirror and lens, and means carried by said handle for making and breaking the lamp-circuit.

5. A combined mouth mirror and lamp for dental use comprising a handle, a casing connected by a universal joint to said handle, a mirror mounted on said casing, a lens mounted opposite said mirror, an electric lamp supported within said casing, conductor-wires leading through said handle to said lamp, and a make-and-break collar carried by said handle.

In testimony whereof I affix my signature in presence of two witnesses.

LYTER H. CRAWFORD.
